(57) **CLAIM**

The ornamental design for a motorcycle or motorcycle replica, as shown and described.

DESCRIPTION

FIG. 1 is a front view of the motorcycle or motorcycle replica showing our new design;

FIG. 2 is a rear view thereof;

FIG. 3 is a top plan view thereof;

FIG. 4 is a right side view thereof;

FIG. 5 is a left side view thereof;

FIG. 6 is a front and left side perspective view thereof;

FIG. 7 is a rear and right side perspective view thereof;

FIG. 8 is a front and right side perspective view thereof; and,

FIG. 9 is a rear and left side perspective view thereof.

The broken lines in the drawings illustrate portions of the motorcycle or motorcycle replica that form no part of the claimed design.

1 Claim, 5 Drawing Sheets
